UNITED STATES PATENT OFFICE.

WALTER HÖHLE, OF BARMEN, GERMANY.

DESIGN FOR A BRAIDED FABRIC FOR INCANDESCENT GAS-MANTLES.

43,744.

Specification for Design.

Patented Mar. 25, 1913.

Application filed November 9, 1911. Serial No. 659,447. Term of patent 7 years.

To all whom it may concern:

Be it known that I, WALTER HÖHLE, manufacturer, a subject of the Emperor of Germany, residing at Königstrasse 58, Barmen, Rhenish Prussia, Germany, have invented a new, original, and ornamental Design for Braided Fabric for Incandescent Gas-Mantles, of which the following is a specification, reference being had to the accompanying drawing, forming part thereof.

The figure is a plan view of a braided fabric for incandescent gas mantles.

I claim:

The ornamental design for a braided fabric for incandescent gas mantles as shown.

WALTER HÖHLE. [L. S.]
